SCARFING MACHINE

Gilbert B. Upham, Los Angeles, Calif., assignor to
 Summerbell Roof Structures, Los Angeles,
 Calif., a corporation of California

Application May 11, 1953, Serial No. 354,123

5 Claims. (Cl. 144—134)

1

This invention relates to a scarfing machine for forming oppositely disposed scarfs on the end of a wooden structural element.

Explanatory of the present invention, the use of oppositely disposed scarfs on the ends of wooden structural elements which are to be connected together either in alignment or substantial alignment has proven quite advantageous. Such double-scarfed joints as are capable of being produced thereby not only enable the structural elements to be satisfactorily glued together but also enable the transmission of stresses from one element to the adjacent element. Examples of structures wherein these double-scarfed joints are used are disclosed in United States Letters Patent No. 2,409,383 to A. V. Pedersen issued October 15, 1946 and 2,478,421 issued August 9, 1949 to A. V. Pedersen.

An object of the present invention is to provide a machine which will enable these double scarfs to be quickly and accurately formed on the end of a wooden board or timber. In the usual situation the slope of each scarf is in the neighborhood of one to ten or one to twelve, so that the end of the scarf tapers to a thin edge. In cutting such scarfs on the end of the board or timber, it is desirable to be able to cut the wood rapidly but at the same time avoid damaging or splitting the wood at such thin edge. It is also essential that the scarfed tongues mutually meet in the same vertical plane so that a tight joint may be secured between the structural elements when they are mutually assembled in end-to-end relationship. It is therefore a further object of the present invention to provide a machine which will satisfactorily meet these requirements.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation of the scarfing machine embodying the present invention, parts being broken away and shown in vertical section;

Fig. 2 is a partial view illustrating details of one of the routers forming a part of the machine;

Fig. 3 is a partial view taken substantially upon the line 3—3 upon Fig. 1 to illustrate the stop and hold down forming a part of the machine, the stop being shown in its elevated position;

2

Fig. 4 is a view similar to Fig. 3 but illustrating the stop in its retracted position;

Fig. 5 is a partial view taken substantially upon the line 5—5 upon Fig. 2;

Fig. 6 is a partial view illustrating the scarfs as having been formed on a structural element; and

Fig. 7 is a partial view in perspective illustrating the scarfed end of the structural element.

Referring to the accompanying drawings wherein similar reference characters designate similar parts throughout, the end product produced by the scarfing machine herein disclosed is illustrated in Fig. 7 wherein a board or timber 10 has two oppositely disposed scarfs formed thereon dividing the end of the board into two tongues 11 and 12. The tongue 11 is scarfed on its underside, as indicated at 13, while the tongue 12 is scarfed on its upper side, as indicated at 14. These tongues are defined from each other by sides 15 and 16 which are arranged in the same vertical plane. Usually this plane is located on the longitudinal center line of the board or timber 10, although this is not necessarily so.

The scarfing machine embodying the present invention comprises a suitable frame 20 on which there is a suitable support 21 having a lateral guide 22 against which the board 10 may be positioned. On the frame 20 there is a rocker shaft 23 carrying a stop 24 that is capable of swinging upwardly beyond the end of the support 21 so as to be engaged by the end of the board. Thus, when the board 10 is pressed laterally against the guide 22 and has its end engaging the stop 24, the board will be accurately positioned with relation to the cutters of the routers, hereinafter to be described.

The rocker shaft 23 carries a crank 25 having a pin and slot connection 26 with the piston rod of a piston, not shown, which is reciprocable within a pneumatic cylinder 27 that is supplied with air pressure, such as through a hose or conduit 28. Thus, when the piston within the cylinder 27 is actuated, the rocker shaft 23 may be partially rotated to swing the stop 24 downwardly from the position shown in Figs. 1 and 3 into the position shown in Fig. 4. On the other hand, when the air pressure is supplied to the opposite end of the cylinder 27, the piston is moved in the reverse direction, swinging the stop from the position shown in Fig. 4 into the position shown in Fig. 3, so as to be engageable by a subsequent board.

As will be noted from an inspection of Fig. 4, the support 21 is cut away, as indicated at 29,

for a distance from the end of the support somewhat greater than the length of the scarf that is to be cut so that at the end of the board 10 only a portion of the underside of the board is actually engaging and resting on the support.

Over the support 21 there is a hold down 30 suspended by means of springs 31 and 32 from brackets 33. These brackets, in turn, support pneumatic cylinders 34 and 35 within which there are reciprocable pistons. The rod of the piston in the cylinder 35 is directly connected to the hold down 30 but the rod of the piston in the cylinder 34 is equipped with a presser foot 36 engageable with the forward end of the hold down. This presser foot is urged into its uppermost position by a tension spring 37. The pneumatic cylinders 21, 34 and 35 may all be connected to the same source of supply of compressed air so that after the board 10 has been positioned on the support against the guide 22 and against the stop 24, on supplying air to the pneumatic cylinders the stop 24 may be swung downwardly into the position shown in Fig. 4, and, simultaneously, the hold down 30 will be pressed downwardly into engagement with the top of the board to clamp it against the support. The hold down is cut away, as indicated at 38, similarly to the cut away portion 29, so as to avoid any interference with the cutters of the routers.

On the frame 20 there are two rails 39 and 40 which provide ways that mutually diverge with relation to each other in a direction longitudinally of the board 10. In the preferred arrangement, the rail 39 is pivotally mounted on the frame, as at 41, and the rail 40 is pivotally mounted on the frame, as indicated at 42. This pivotal mounting enables these ways to be adjusted in cutting scarfs having different slopes. The rails are maintained in adjusted positions by means of eye bolts 43 which are pivotally mounted on the frame 20 and which extend through ears on the rails 39 and 40 respectively. By adjusting the nuts on these eye bolts, the tilt of each of the rails can be varied, and after the adjustment has been made, the rails may be effectively locked in adjusted positions. On the upper rail there is slidably or movably mounted a carriage 44 which carries an electric motor 45 that drives a spindle 46 on which a routing cutter 47 is mounted. In a similar manner, a carriage 48 is slidably or movably mounted on the lower rail 39, and carries an electric motor 49 that drives a spindle 50 on which a routing cutter 51 is rotatably mounted.

A chain 52 is connected to the carriage 48 and passes over a sprocket 53 at the end of the rail 39. From this sprocket the chain passes over sprockets 54, 55, and 56, and is connected to the carriage 44. Another chain 57 is connected to the carriage 44 and is trained over a sprocket 58. This chain is trained over sprocket 59 and a sprocket behind the sprocket 55 and over sprocket 60. In association with the carriage 48 there is a pneumatic cylinder 61 within which there is a piston 62, the rod of which is connected to the carriage 48. The ends of this pneumatic cylinder are supplied with air under pressure by conduits or hoses 63. With this arrangement it will be noted that if air is supplied to the pneumatic cylinder 61 to force the piston 62 toward the right as viewed in Fig. 1, the chain connections afforded by the chains 52 and 57 cause both carriages 44 and 48 to simultaneously advance toward the board 10. Conversely if air pressure is supplied to the opposite end of the cylinder 61 to force the piston 62 toward the left as viewed in Fig. 1,

both carriages 44 and 48 will be caused to simultaneously recede or retract away from the board 10.

As will be observed from Fig. 1, the spindle 50 is disposed somewhat in advance of the spindle 46, which enables the cutting blades on the routing cutters 47 and 51 to cut to the same vertical plane, represented by the line P on Fig. 5, without danger of interference between the blades.

Behind the routers there may be a conduit 64 through which air is drawn so as to carry away cuttings cut from the board by the router cutters.

It will be appreciated that when a board has been positioned on the support and is clamped thereon by the hold down 30 and the stop 24 has been swung downwardly into the position shown in Fig. 4 that when air is supplied to the air cylinders 61, both router cutters 47 and 51 will be advanced towards the end of the board. However, these router cutters are routing in different planes and are caused to advance toward the end of the board upon divergent paths due to the divergency of the rails 39 and 40. The cutter 47 will, consequently, cut the scarf 14 on the tongue 12 up to the vertical side 15. Simultaneously, the router cutter 51 will cut the scarf 13 on the tongue 11 up to the side 16. In this manner oppositely disposed scarfed tongues may be cut in a single operation on the end of the board. These tongues will be accurately formed without danger of splitting or otherwise damaging the thin ends of the tongues. Structural elements whose ends have been formed in this manner may be mutually assembled together and when glue is applied to the scarfed faces 13 and 14, a very sturdy and highly satisfactory joint between adjoining structural elements can be obtained.

When the cutting operation has been completed and the routers have been returned to their initial positions, as shown in Fig. 1, the air may be reversed in the cylinders 21, 34, and 35, causing the hold down 30 to be lifted to release the board that has been scarfed and causing the return of the stop 24 so that it may function to properly locate a succeeding board positioned on the support 21.

As will be observed from Fig. 2, the motors that carry the spindles and router cutters are mounted for vertical adjustment as well as lateral adjustment on their respective carriages. This enables the construction to be used on boards of varying thicknesses and varying widths. For example, with a board of greater thickness than that shown, the upper routing cutter would be elevated. Likewise, with a board of greater width than that shown both routing cutters may have to be shifted so that the common vertical plane to which both routing cutters cut will be located centrally of the board.

From the above described construction, it will be appreciated that the improved scarfing machine enables oppositely disposed scarfs to be cut and tongues to be formed on the end of a board or timber. Such operation may be performed quite rapidly and with great accuracy. If it is desired to increase or decrease the slope of the scarfs 13 and 14, this may be readily accomplished by adjusting the positions of the rails by means of the eye bolts 43.

Various changes may be made in the details of construction without departing from the spirit and scope of the invention as defined by the appended claims.

I claim:

1. A machine for cutting mutually opposed scarfs on an end of a wooden element comprising

ing a frame, a support on said frame on which the element may be placed, mutually divergent ways pivotally mounted in the same vertical plane on said frame adjacent the support and on opposed sides thereof, means for altering the divergence of each of said ways relative to the other, a router mounted for movement along each of said ways, said routers being spaced both laterally and vertically from each other, and means for advancing and retracting the router along said ways to cause them to move toward and away from the wooden element.

2. A machine for cutting mutually opposed scarf's on an end of a wooden element comprising a frame, a support on said frame on which the element may be placed, a stop at the end of the support against which an end of the element may be positioned, ways pivotally mounted in the same vertical plane on said frame adjacent the support and on opposed sides thereof which are mutually divergent in a direction longitudinally of the element, means for altering the divergence of each of said ways relative to the other, a router mounted for movement along each of said ways, said routers being spaced laterally and vertically from each other, means for advancing the routers simultaneously along said ways, and means for moving the stop out of the path of the routers in advance of the advancement of the routers into engagement with the element.

3. A machine for cutting mutually opposed scarf's on an end of a wooden element comprising a frame, a support on said frame on which the element may be placed, a stop at the end of the support against which an end of the element may be positioned, ways pivotally mounted in the same vertical plane on said frame adjacent the support and on opposed sides thereof which are mutually divergent in a direction longitudinally of the element, means for altering the divergence of each of said ways relative to the other, a router mounted for movement along each of said ways, said routers being spaced both laterally and vertically from each other, a hold down means engageable with the element, and

means for moving the hold down means into engagement with the element and simultaneously moving the stop out of the path of the routers in advance of the advancement of the routers into engagement with the element.

5 4. A machine for cutting mutually opposed scarf's on an end of a wooden element comprising a frame, a support on said frame on which the element may be placed, mutually divergent ways pivotally mounted in the same vertical plane on said frame adjacent the support and on opposed sides thereof, means for altering the divergence of each of said ways relative to the other, a router mounted for movement along each of said ways, said routers being spaced both laterally and vertically from each other, and means for advancing and retracting the routers along said ways to cause them to move toward and away from the wooden element, said ways being adjustable as to inclination whereby the slopes of the scarf's cut by the routers may be varied.
